EUGENE J. FEHR, CARL LUTE, AND KENNETH J. TOBIN, OF CHICAGO, ILLINOIS,
ASSIGNORS TO CAMEL COMPANY, OF CHICAGO, ILLINOIS, A CORPORATION OF
ILLINOIS

SUPPORTING MEANS FOR CAR DOORS

Application filed September 20, 1929. Serial No. 393,914.

This invention relates to supporting means for car doors and concerns itself with a structure that provides for considerable in and out movements of the door together with means for guiding and forcing the door to partake of such movements.

The invention comprises the novel structure and combination of parts hereinafter described and more particularly pointed out and defined in the appended claims.

In the accompanying drawings which illustrate a preferred form of this invention, and in which similar reference numerals refer to similar features in the different views:

Figure 1 is an elevational view of a car door with adjacent parts of the car involving this invention.

Figure 2 is an enlarged broken sectional view taken upon the line II—II of Figure 1.

Figure 3 is a view similar to Figure 2, illustrating the door in elevated position.

Figure 4 is an enlarged sectional view taken upon the line IV—IV of Figure 1.

Figure 5 is an enlarged sectional view taken upon the line V—V of Figure 1.

Figure 6 is an enlarged sectional view taken upon the line VI—VI of Figure 1.

Figure 7 is an enlarged fragmentary longitudinal section taken through the lever connection between the two retainer sections.

Figure 8 is an enlarged sectional view taken upon the line VIII—VIII of Figure 7.

Figure 9 is a sectional view taken in the same plane as Figure 8 but with parts omitted and showing the door in elevated position.

Figure 10 is an enlarged sectional view taken upon the line X—X of Figure 7.

In referring to the drawings which illustrate one embodiment of this invention, the door is represented by the reference numeral 1 and is provided along its lower margin with end castings 2 and 3 and center castings 4 and 5, which are for a similar purpose in that they support and carry a ball or roller retainer 6, which is preferably made in two similar sections and joined at their adjacent ends in a manner that will later appear.

The castings 2, 3, 4 and 5 have bearing re-

cesses for receiving bearing plugs 7 which are secured in the ends of the ball retainer sections. Each recess in the different castings has an upwardly extending groove or notch 8, best shown in Figure 3. It will be noted that the notch 8 in each casting is eccentrically positioned with respect to the center line thereof and the outer wall of each notch is flush with the outer wall of the bearing recess. The inner wall of each notch terminates in a substantially right angle, the lower surface of which forms a shoulder 9 which in turn merges into a downwardly and inwardly sloping portion 9a as shown in Figures 8 and 9. Each bearing plug 7 has an upwardly extending projection 10 at one side that is adapted for entering the notch 8 in the casting 1 and a shoulder 7a terminating in a fulcrum point 7b upon the inner or opposite side that is adapted for engaging the shoulder 7a at its juncture with the sloping part 9a as shown in Figure 9 when the same is rocked outwardly with respect to the door for elevating the door.

The center plugs 7 are rigidly connected or formed with an operating handle 11 which is adapted to be swung transversely of the car for oscillating the ball retainer as shown in Figure 3 elevating the door and supporting the same upon its rollers 12 which travel upon a track 17.

The roller retainer sections are preferably formed from sheet metal which is bent or stamped to provide a longitudinal channel or groove with slightly inturned edges 6a for retaining the rolling elements 12 which are in the form of balls for relative longitudinal movement thereof. The retainer is so formed that the balls contact on a chord less than the diameter so that the same will only roll a predetermined distance relative to the retainer while the door is moving to its open or closed position. When the door is lowered, the retainer will rock so as to frictionally engage the track as shown in Figures 8 and 10, so the same constitutes combined frictional and anti-frictional supporting means. The castings 2, 3, 4, and 5 on the door are also provided with track engag-

ing positions 2a and 4a for supporting the door upon the track.

Means are provided for moving the door inwardly when it is lowered so that the retainer rests upon the track, and for moving it outwardly when it is elevated so that it is supported upon the rollers. To this end, a weather strip 13 in the form of an angular bar is attached to the door along the upper 10 margin of the door opening. This angular bar 13 has an attaching flange 13a that is attached to the side plate 14 of the car, and an outstanding flange 13b, having a downwardly and inwardly sloping lip or portion 13c. The door carries a pair of spaced 15 guide brackets 15 which have upwardly and outwardly sloping surfaces 15a that extend substantially parallel to the sloping surfaces of the lips 13c. Along the upper margin 20 of the door, there is secured an angle bar 16. It will be noted that one flange of this angle bar is attached to the door and the other flange is directed outwardly for engaging the sloping lip 13c of the weather angle 25 13. With this construction, it will be apparent that when the door is elevated, the guides 15 will engage the sloping lips 13c and move outwardly carrying the upper end of the door outwardly. On the other hand, 30 when the door is lowered, the angle 16 will ride down the sloping surface of the lip 13c and force the upper end of the door inwardly. The lower part of the door is moved 35 inwardly and outwardly through the rocking movements of the ball retainer which is provided with a wing 6b that swings behind the track and retains the door against outward movement when the same is in its lowered position. This wing 6b will also engage the track 17 and force the lower end of the door inwardly if the door becomes sufficiently removed from the car.

Upon the front door post 28, there is a 45 weather angle 18 (Figure 5) that is deformed to provide a channel or groove 19 to receive an angular weather strip 20 upon the front edge of the door.

Upon the rear door post 21, there is a 50 weather strip 22 (Figure 6) which is deformed to provide an outwardly extending bulge 23 against which the door is adapted to abut. Rearwardly of the bulge 23, there is a groove or channel 24 in a weather strip 22 55 that is adapted for receiving an enlarged flange 25 on an angular weather strip 26 attached to the door, when the door is moved inwardly by the above described means.

A suitable latch 27 is pivoted to the door 60 for engaging over the operating lever 11 for holding the door in its closed position. It will be noted that in its closed position, the door abuts the front door post 28, and the bulge 23 on the rear weather strip 22. In addition, the weather strips on the door coop-

erate with the weather strips on the car for effectively excluding the weather.

The door usually rests in frictional engagement with the track 17 as shown in Figure 2. In this position, the ball retainer 70 frictionally engages the track. When it is desired to open or close the door, the operator will unlatch the handle 11 and swing the same outwardly as shown in Figure 3. This movement of the lever 11 will rock the retainer and force the projections 10 of the plugs 7 downwardly and the fulcrum points 7b thereof upwardly against the casings for 75 elevating the door for supporting the same upon its rollers as shown in Figure 9. It will be understood that the balls 12 form the fulcrum for the lever 11. As the door is elevated, the guides 15 and the rocking movement of the retainer will force the door outwardly as shown in Figure 3. When the lever 11 is released, the door will automatically drop upon the track. In dropping, the door will move inwardly for the reasons 80 previously set forth and bring the weather-excluding features into cooperative relation. 90

We are aware that many changes may be made, and numerous details of construction may be varied through a wide range without departing from the principles of this invention, and we therefore do not purpose limiting the patent granted hereon, otherwise than 95 necessitated by the prior art.

We claim as our invention:

1. The combination with a house car having a door opening with a track adjacent one margin of said opening, of a door for closing said opening, a ball retainer secured to said door for oscillating movements transversely of the door for elevating and lowering the same and cooperating means upon the door and car for moving the door outwardly during its elevating movements, and inwardly during its descending movements. 100

2. In a house car having a door opening with a track adjacent one margin of said opening, a door for closing said opening, a longitudinally extending ball retainer carried by said door for transversely rocking movements, balls carried by said retainer, a member attached to one margin of the door opening, and having an inwardly sloping portion, and means on said door engaging said sloping portion for moving the door inwardly and outwardly. 110

3. In a house car having a door opening with a track adjacent one margin of said opening, a member having an inwardly sloping portion adjacent the opposite margin of said opening, a door supported upon said track and having means engaging both sides of said sloping portion, and transversely rockable means upon the lower portion of the door for elevating the same and moving the same inwardly and outwardly. 120

4. In a house car having a door opening 125

with a track adjacent one margin of said opening, a door for closing said opening, anti-frictional and frictional means carried by said door for optionally engaging said track, a member for operating said means for elevating the door and supporting the same upon said anti-frictional means, a guiding member having an inwardly sloping portion carried by said car, and means on said door 10 engaging said sloping portion for moving said door inwardly and outwardly.

5. In a house car having a door opening with a track adjacent one margin of said opening, a door for closing said opening, a 15 rockable member carried by said door for frictionally supporting said door upon said track when in a predetermined position, anti-frictional means carried by said member for supporting said door upon said track when 20 said member is in a second predetermined position, and guiding means on said car and door for moving the same inwardly into sealing relation with the car when said door is frictionally supported by said member.

25 6. In a house car having a door opening with a track adjacent one margin of said opening, a door for closing said opening, combined frictional and antifrictional means carried by said door for optionally supporting 30 said door upon said track, cooperating weather-proofing guiding means upon said car and door adapted for coming into cooperative relation when said door is frictionally supported upon said track, and means for moving 35 the door inwardly to bring such weather-proofing means into cooperative relation.

7. In a house car having a sliding door, a track, combined frictional and anti-frictional means on said door for alternately supporting said door upon said track through elevating and lowering movements of the door, cooperating means on the door and car for positively moving the door outwardly or inwardly during such elevating and lowering 45 movements, and sealing means for the door adapted for coming into sealing relation when the door is moved inwardly.

8. The combination with a door having castings at its lower margin, a ball retainer 50 having lugs extending into said castings, balls for supporting said retainer, a track for supporting said balls, said castings and lugs having cooperative shoulders adapted to be brought into coacting relation by a rocking 55 movement for elevating the door.

9. The combination with a door, a ball retainer attached to the lower margin of the door for rocking movements for elevating and lowering the door, balls in said retainer, 60 a track for said balls, said retainer having depending portions for engaging said track for moving the door inwardly when said door is lowered.

10. In a house car having a door opening with a track adjacent one margin of said

opening, a member having an inwardly sloping flange adjacent the opposite margin of said opening, a door, means for mounting said door upon said track for inward and outward movement, a pair of members upon said door forming a guideway for receiving said inclined flange, a weather strip adjacent the rear end of said door opening and having a vertical groove and a weather strip upon the rear margin of the door adapted to move into and out of said groove during inward and outward movements of the door.

70 11. In a house car having a door opening with a track adjacent one margin of said opening, a member having an inwardly sloping flange attached to the car adjacent the opposite margin of said opening, a door, means for mounting said door upon said track for inward and outward elevating and lowering movements, a pair of members on said door forming a guideway for receiving said inwardly sloping flange and cooperating with said flange for forcing the door inwardly and outwardly during its elevating and lowering movements.

75 In testimony whereof, we have hereunto subscribed our names at Chicago, Cook County, Illinois.
